UNITED STATES PATENT OFFICE.

APOLLINARIS HREBICEK, OF BINGERBRÜCK, GERMANY.

SUBTERRANEAN CURRENT TRANSMISSION FOR ELECTRIC TRAMWAYS OR RAILWAYS.

SPECIFICATION forming part of Letters Patent No. 691,381, dated January 21, 1902.

Application filed September 12, 1899. Serial No. 730,238. (No model.)

To all whom it may concern:

Be it known that I, APOLLINARIS HREBICEK, a subject of the Emperor of Austria-Hungary, residing at Bingerbrück, in the Kingdom of 5 Prussia, Germany, (whose full postal address is Benedictusgarten, Bingerbrück, Prussia,) have invented certain new and useful Improvements in Subterranean Current Transmissions for Electric Tramways or Railways, 10 (for which I have applied for patents in Germany, dated February 24, 1899, and in France, No. 286,949, dated March 18, 1899,) of which the following is a specification.

This invention relates to subterranean current transmission for electric tramways and railways, the essential feature of which is that a channel or conduit in which is arranged the working circuit is opened in sections by the approaching vehicle and closed again behind such vehicle.

The accompanying drawings show how this invention may be carried into effect.

Figure 1 shows a transverse section through the arrangement. Fig. 2 shows a longitudinal section therethrough. Fig. 3 is a plan. Figs. 4 and 5 are two views of the device for opening the conduit. Figs. 6, 7, and 8 show the sliding conduit-cover. Figs. 9 and 10 show the current-receiver.

Conduit 1 is arranged on brackets 2, the working circuit consisting of a suitable metal. The conduit 1 has at the top a longitudinal slot, closed by sliding covers 4. The latter are shown in Figs. 6, 7, and 8 and are secured 30 in closed position by springs 5. Their upper surfaces have grooves 6, which start at each end of the cover 4 on the same side, run obliquely to the opposite side and thence parallel to the longitudinal edge to each end of 35 the slide. The slides 4 move in guides 7, arranged at the edge or neck of the conduit-slot and situated between the rails 8. On the carriage 9 are arranged cover-opening devices 10, which carry at their lower ends, Figs. 45 2, 4, and 5, rollers 11 and 12, by which they engage in the groove 6, and thereby push aside the cover 4 and open the conduit when the carriage or vehicle 9 passes. On the support 10 is arranged a brush 13, which frees 50 the groove 6 from dust and dirt. A current-receiver 14 is attached below the vehicle 9 and extends in the open channel-slot. The

current-receiver 14, as shown in Figs. 1, 2, 9, and 10, consists of a contact-roller 15, contact-brushes 16, and circuit-wires 17, leading 55 to the vehicle-motor, and carries on one side rollers 18, which serve to keep the cover 4 open as long as the current-receiver 14 runs within the limits of this cover-section, the opening device 10 being already in the section of the following cover 4 and commences to open the same. As the opening device 10 opens the cover by the oblique groove 6 in the first half of the cover and keeps it open by the straight groove 6 in the second half of 60 the cover and as the rollers 18 of the current-receiver 14 must engage before the conduit-opening device leaves, the distance between the conduit-opener 10 and the current-receiver 14 must be larger than one-half of the 65 length of the cover and less than the whole length of the cover. It is preferable to have two conduit-opening devices on the vehicle, one at each end, thus avoiding the turning 70 of the vehicle. The opening devices 10 are 75 lowered into and raised out of the groove 6 from the driver's platform by bevel-gear mechanism 19 and screw and pinion 20. When the screw 22 descends, the current-receiver 14 is carried in a circular curve around 80 the center 23 to the conduit-conductor by means of similar driving mechanism 24 and connecting-rod 21. When engaged, the current-receiver 14 obtains the required elastic counter-pressure against the conductor 3 by 85 springs 25.

The operation is as follows: Supposing that the vehicle 9 stands in the departure-station over an open piece of the conduit-slot. By suitable rotation of the gearing 19 and 20 the 90 opening device 10, situated forward in the direction of driving, is screwed down to the proper level, and by a suitable rotation of the gearing 24 22 the current-receiver is turned down, so that it bears elastically under the pressure of the springs 25 on the conduit-conductor. When now the driver turns the contact-switch for the motor, the vehicle 9 moves, the opening device 10 enters into the groove 6 of the nearest cover 4, and as 100 this groove is oblique and the device 10 is fixed to the vehicle 9 the cover 4 is pushed aside, and the conduit-slot is thus opened. This movement of the opening device 10 is

continued until the latter has reached the middle of the cover 4. Then the groove 6 runs parallel with the longitudinal axis of the vehicle, and the slot is therefore not opened 5 farther, but only kept open. Before the opening device leaves this cover-section 4 the current-receiver 14 has reached it and keeps it open by the rollers 18. In the meantime the opening device 10 enters the oblique 10 groove 6 of the following cover 4 during the further movement of the vehicle 9, opens it, and keeps it open until the current-receiver 14 enters from the preceding cover-section 15 and holds it open, the preceding cover being closed through the pressure of the springs 5. This operation is repeated the whole length of the line of tram or rail ways. When the vehicle has arrived at the end of the line, the opening device 10 is raised by the gearing 19 20, and if it is desired that the vehicle shall make a return journey the opening device 10 at the other end of the vehicle is lowered by the gearing 19 20 belonging to it. If it is desired that the vehicle be placed out of service 25 for the time being, the current-receiver 14 is placed out of contact with the working circuit or conductor by corresponding rotation of the gearing 22 and 24.

What I claim, and desire to secure by Letters Patent of the United States, is—

1. In an electric railway, an underground conduit provided with a series of independent sliding normally closed covers, provided on the surface with a groove 6 extending 35 obliquely and longitudinally substantially as and for the purposes described.

2. In an electric railway, an underground conduit provided with a series of independent sliding normally closed covers, provided on the surface with a groove 6 6 extending 40 obliquely and longitudinally and oppositely arranged, substantially as and for the purposes described.

3. In an electric railway, an underground conduit provided with a series of independent sliding normally closed covers, provided on the surface with a groove 6 extending 45 obliquely and longitudinally, a traveling vehicle, a collector carried thereby and extending into the conduit through the opened 50 covers, and a cover-opener carried by said vehicle and engaging the groove 6 of successive covers, substantially as and for the purposes described.

4. In an electric railway, an underground conduit provided with a series of independent sliding normally closed covers, provided on the surface with a groove 6 extending 55 obliquely and longitudinally, a traveling vehicle, a collector carried thereby and extending 60 into the conduit through the opened covers, a cover-opener carried by said vehicle and engaging the groove 6 of successive covers, and a brush 13 extending in said groove in advance of the cover-opener, substantially as and for the purposes described.

In testimony whereof I have hereunto set my hand in the presence of two witnesses.

APOLLINARIS HREBICEK.
